UNITED STATES PATENT OFFICE

2,515,752

STRETCHER PRESS

William A. Weightman, Philadelphia, Pa., assignor to The Budd Company, Philadelphia, Pa., a corporation of Pennsylvania

Application December 13, 1944, Serial No. 567,983

7 Claims. (Cl. 153—32)

1

The invention relates to a stretcher press and more particularly to a machine of this type adapted for simultaneously bending and stretching profiles into curved forms.

Among the objects of the invention is a machine of the indicated type which is easily operated and which allows the production of a great variety of shapes including shapes with curvatures in more than one plane.

Another object of the invention is a machine of the indicated type which can easily and speedily be adapted or changed to the production of differently shaped articles.

The aforesaid objects and other objects and advantages are achieved by a machine having pairs of power driven independently movable and controllable stretching elements.

The invention and its objects and advantages will be more easily and fully understood from the embodiment illustrated in the attached drawings and described in the following.

In the drawings:

Figure 1 is a plan view of a machine showing diagrammatically the control circuits for the different movable elements, certain parts being broken away;

Figure 2 is a section on a larger scale along line 2—2 of Figure 1 with one of the arms swung about 90° from the position shown in Figure 1;

Figure 3 is a section through one of the arms along line 3—3 of Figure 2 on a still larger scale; and

Figure 4 is a fragmentary section along line 4—4 of Figure 1 on a scale larger than that of Figure 2.

A floor 10 supports a base plate 11. Part of the plate 11 covers a well 12 in the floor 10 the side walls of which are formed by beams 13. An upright wall 14 has its lower margin secured to a reinforcement 15 of the base plate 11 and its upper margin to a table top 16. Webs 17, 18 and 19 interbrace said wall 14, said reinforcement 15 and said top 16. The web 18 is arranged along the vertical center line of the members 11, 14, 15 and 16. The webs 17 and the wall 14 are further interbraced by horizontal webs 20.

The upper side of the top plate 16 is adapted for the securement thereto of a bending die 21, as by means of bolts 22. The free edge of the top 16 running parallel to the wall 14 is reinforced by an upwardly directed flange 23. The latter has screw threaded therein bolts 24 serving for the adjustment of the die 21. The die

2

21 and its use will be described more fully later on.

Secured to the bottom plate 11 is a pair of gibs 25 which run parallel to each other and to the wall 14. Another gib 26 is secured to the wall 14 and extends horizontally on both sides of the web 18.

A pair of generally U-shaped structures 27 engage with mating gibs 28 and 29, respectively, the aforesaid gibs 25 and 26 so that the structures 27 are slidably guided on the structure formed by the plate 11 and the wall 14. Each structure 27 has a vertical web 30 carrying the gibs 29, a lower horizontal arm 31 of considerable length carrying the gibs 28 and a short horizontal upper arm 31'. The lower arm is in the form of a circle segment and has secured to its periphery a rack 32.

Secured to the underside of the plate 11 and arranged in the well 12 is an electric motor 33 which through gears 34 drives a short shaft 35 rotatably supported in bearings 36 secured to the top of the plate 11 and which is controlled by the diagrammatically illustrated switch 33'. The shaft 35 extends parallel to the hereinbefore described gibs 25 and is arranged co-axially with a pair of screw threaded shafts 37 the outer ends of which are supported rotatably but axially immovably in bearings 38 likewise secured to the plate 11. The screw threaded portions of the shafts 37 engage nut members 39 secured to the arms 31. Between the inner end of each shaft 37 and the adjacent outer end of the shaft 35 is arranged a coupling 40. The two couplings 40 are independently controllable, as by linkage and lever systems 41, 42.

A pair of generally horizontally arranged arms 43 have their inner ends journaled rotatably about a vertical axis to the arms 31 and 31' of the structure 27 at 44. At some distance from the journal 44, each arm 43 rests by means of rollers 45 on the top surface of a horizontal extension 46 of the arm 31. Each arm carries a motor 47 which through gears 48 drives a pinion 49 engaging one of the racks 32. The motors 47 of the two arms are controllable independently of each other by a pair of control means diagrammatically illustrated at 50 in Figure 1.

Each arm 43 extends outwardly beyond the roller support 45, 46 and has its extended portion provided with a pair of horizontally spaced vertical gibs 51. The gibs 51 are engaged by correspondingly shaped gibs 52 provided on a horizontal beam structure 53. Each beam structure 53 carries an electric motor 54 which through

gears 55, drives a horizontal shaft 56 rotatably supported in bearings 57 on downward extensions 58 of the beam structure 53. The shaft 56 has secured thereto near each of its ends a worm 59 which is in driving engagement with a worm wheel 60. Each worm wheel 60 is held between lugs 61 of the extension 58 and is secured to a screw threaded shaft 62. The screw threads of the shaft 62 engage the correspondingly screw threaded interior of a lug 63 formed integrally with the respective arm 43. Here again each of the two motors 54 is independently controllable by a pair of control means 64 diagrammatically illustrated in Figure 1.

Each beam structure 53 carries in bearings 65 rotatably but axially stationarily a second shaft 66 which is screw threaded over the greater part of its length. The shaft 66 is in driving connection with a motor 67 by means of gears 68. The motor 67 is supported by the respective beam structure 53 and is controllable independently of the corresponding motor on the other arm by the control means 69 diagrammatically shown in Figure 1.

A pair of sleds 70 are slidably supported by gib 71 formed thereon and correspondingly shaped guideways 72 of the beam structures 53. Each sled 70 is in screw threaded engagement with one of the shafts 66 so that rotation of the latter causes the sled to move along its supporting beam structure 53.

A hydraulic cylinder 73 is journalled at 74 to lugs 75 integrally secured to the sled 70. The opposite end of the cylinder 73 has rollers 76 which run on a segment shaped portion 77 of the sled 70. A piston 78 in the interior of the cylinder 73 is connected to a rod 79 which carries a vise 80 swingably around a horizontal bolt 81.

The vises 80 are adapted for firm but releasable engagement of one end each of a workpiece 82 by means of jaws 83. The drawings show an angle section workpiece but it should be understood that a great variety of cross-sections may be bent by the illustrated machine. Of course, the jaws of the vises 80 and the die 21 have to be shaped in accordance with the cross-section of the workpiece to be made.

Pressure medium may be admitted to and discharged from the cylinders 73 by means of the pipe lines 84 and the valves 85 and the return of the pistons may be effected by springs 86. The pressure medium is supplied by the pump 87 driven by motor 88.

The drawing clearly shows the substantially symmetrical construction of the machine relative to a vertical transverse plane and the provision of most elements in pairs even though, occasionally for simplicity's sake, one of the elements only has been referred to in the foregoing description.

The operation of the new machine under different conditions will now be briefly described.

If, as in the illustrated embodiment, the die 21 has a working surface which is curved in one plane only and which is symmetrical to a center line, the die is placed in the machine so that its center line coincides with the center line of the machine. The location of the journals 44 is adjusted by means of the motor 33 and the transmissions driven thereby. The sleds 70 are moved by means of the motors 67 along the beams 53 to positions at which the vises 80 are at a distance from each other equaling about the length of the workpiece 82. Also the height of

the vises 80 is adjusted so that they are at the same level with the working surface of the die 21; this adjustment is done by the motors 54 and the transmissions between them and the beam 53.

After these adjustments the workpiece 82 is placed with its ends in the vises 80 and secured therein while the arms 43 are in the position illustrated in Figure 1. Pressure medium is now admitted to the cylinders 73 so that the workpiece 82 is stretched and, while the workpiece is under tension, the arms 43 are swung toward each other about their pivots 44 by means of their motors 47, the transmissions 48, the pinions 49 and the racks 32. The tension of the workpiece 82 may be kept constant during the entire bending operation by reference to a pressure gauge attached to the cylinders 73, to any part of the conduits for the pressure medium or to the pump 87.

If the working surface is more complicated than illustrated, for instance longer, non-symmetrical and in addition curved in vertical direction differently on both sides of its middle plane, then each arm and the elements attached thereto have to be moved independently of each other by means of the hereinbefore described motors and control mechanisms 50, 64, 69. For instance, one vise 80 may be moved upward by means of the motor 54 with its supporting beam 53 and sled 70 to the position illustrated by dot-and-dash lines in Figure 2, whereas the other vise 80 may be kept dependent upon the form of the die, on the original level or may even be moved downwardly by its motor 54.

Similarly each of the arms 43 may be independently moved, according to laws dictated by the form of the die. This independent movement does not only apply to the swinging about the journals 44, but even the location of the journals may be changed during the bending and stretching operation.

No attempt is made to illustrate and describe in detail any of those many forms which may be made on the new machine by proper coordination of the different independent movements. Anybody skilled in the art knows the problems and will easily recognize the possibilities offered by the new machine and how to operate it so as to cope with any one of such problems.

The invention is not restricted to the details of the illustrated embodiment. For instance, certain parts of the machine may be omitted while others may be substituted by equivalent means. Consequently, protection is sought for the invention as broadly as covered by the spirit and the language of the attached claims.

What is claimed is:

1. In a stretching and bending machine, a base structure, means on said base structure for supporting an arm swingable about an axis, a forming die stationarily supported on said base structure in the region of said axis, an elongated structure coextensive with at least a major portion of said arm and supported thereby movably back and forth in a direction generally parallel to said axis of rotation, a sled slidable on said structure back and forth radially with respect to said axis, means supported on said sled for firmly holding a workpiece, and means for holding a workpiece at a distance from the point held by the aforesaid holding means.

2. In a stretching and bending machine, a base structure, means on said base structure for supporting an arm swingable about an axis, a forming die stationarily supported on said base struc-

ture in the region of said axis, an elongated structure coextensive with at least a major portion of said arm and guided thereon movably back and forth in a direction generally parallel to said axis of rotation, a sled slideable on said elongated structure back and forth radially with respect to said axis, means supported on said sled for firmly holding a workpiece, means for holding a workpiece at a distance from the point held by the aforesaid holding means, a motor supported by one of said arm and said elongated structure, a transmission between said motor and other of said elongated structure and said arm so as to move said elongated structure on said arm during the operation of the machine.

3. In a stretch forming machine: a support and a forming die mounted thereon, a pair of means for firmly holding a workpiece in two spaced regions thereof and for stretching the workpiece between said means, an arm rotatable about an axis relative to said support, means on said arm for supporting only one of said holding means movably in a direction extending about parallel to the axis of rotation and at a distance from said die mounted on said support, while said workpiece is held by said pair of holding means in stretched condition in contact with said die.

4. In a machine for stretching and bending, a base, and a forming die supported thereon, a pair of devices for immovably engaging spaced points of a workpiece and for stretching it between them, means for supporting said devices on said base, said supporting means being adapted for moving the devices independently of each other in three different directions relative to said die supporting means which directions define coordinate planes of a spacial coordinate system, while said workpiece is held by said engaging devices in stretched condition in contact with said die supported on said base.

5. In a machine for stretching and bending, a base, and a forming die supported thereon, a pair of devices for immovably engaging spaced points of a workpiece and for stretching it between them, means for supporting at least one of said devices on said base and for moving it independently of the other device in three coordinate planes relative to said die supporting means while said workpiece is held by said engaging devices in stretched condition in contact with said die supported on said base.

6. In a stretching and bending machine, a supporting structure, a forming die supported

thereon, a pair of arms swingable about generally parallel axes relative to said structure, means on each of said arms for gripping and stretching a workpiece, a supporting device and power actuated means for each of said gripping means adapted for moving the latter in the direction of its respective arm, and power means controllable independently of said first-named power operated means for moving said gripping means relative to said supporting structure in a direction generally parallel to the direction of said axes, while said workpiece is held by said gripping and stretching means in stretched condition in contact with said forming die.

15 7. In a machine for stretching and bending, a base, a forming die supported thereon, a pair of devices for holding and stretching a workpiece between them, means for supporting at least one of said devices on said base for movement independently of the other device in three intersecting directions defining three coordinate planes, and three separate and separately controllable motors each of which is adapted for moving the respective device in one of said different directions while the workpiece is held by said stretching devices in contact with said forming die supported on said base.
